UNITED STATES PATENT OFFICE.

JOSEPH A. GROEBLI, OF NEW YORK, N. Y.

BEAD-SEWING MACHINE.

1,356,762.

Specification of Letters Patent. Patented Oct. 26, 1920.

Application filed November 10, 1917. Serial No. 201,259.

To all whom it may concern:

Be it known that I, JOSEPH A. GROEBLI, a citizen of the United States, and a resident of the city, county, and State of New York, 5 have invented certain new and useful Improvements in Bead-Sewing Machines, of which the following is a specification.

My present invention relates to improvements in machines for sewing articles, such 10 as beads, onto fabrics. The machine is adapted to attach any small articles such as beads which are strung upon a thread, to a fabric, by means of stitches formed with the thread on which the articles are strung. In 15 the following description and claims I use the term beads in the broad sense to cover any form of article which may be strung on a thread.

In U. S. Patent No. 1,041,780 dated October 22, 1912, I showed and described a machine for attaching beads or similar articles to fabric by forming stitches in the fabric with the thread on which the beads are strung. That machine is adapted to attach 25 the beads without the use of separating threads wound spirally around the beads and original thread and without the use of a separate or stitching thread in addition to the one on which the beads are originally 30 strung. In U. S. Patent No. 1,073,344 dated September 16, 1913, I showed and described a machine of a similar nature but with the additional advantage that the beads could be attached not only in a straight line but in 35 any desired formation.

The present invention is adapted for the same general purposes as the machines of my said prior patents. In the present machine I have provided additional features 40 which insure the regular and unfailing feeding of the beads and their advancement to the point of their attachment to the fabric.

One branch of my invention relates to the means for primarily holding back the beads 45 from the source of supply and for allowing them to advance singly toward the stitching mechanism. This branch of my invention is intended to provide a simple and efficient automatic device for feeding or separating 50 the beads as they first leave the source of supply in order that the operator will not be obliged to give any attention to the feeding of the beads where the string of beads moves into the vertical position, during the operation of the stitching mechanism. This 55 preliminary feeding or separating device is

preferable in order that the whole supply of beads shall not rest upon or collect in too great numbers near the final separating device and the stitching mechanism. This preliminary feeding or separating device not only regulates or controls the separation of the beads as they leave the source of supply but it also assists in the feeding or advancement of the beads as they are separated.

The final separating device is not only adapted to separate the beads on their thread as they approach the stitching position but it is intended to positively move the beads down to the point of attachment to the fabric, so that the beads will not be held back by any friction on the thread but each one will be advanced to final position in proper time in relation to the stitching operations. This branch of the invention is disposed to 75 operate on the beads between the final separating device (if more than one separating device is used) and the fabric and it is preferably so constructed that the action of the thread looper will coöperate to feed the 80 beads to the fabric.

Another feature of improvement relates to the final bead separator and this is intended to prevent the beads from passing the separator except as intended, even if the 85 thread should become momentarily slack.

In the drawings forming part of this application,

Figure 1 is an elevation of the principal parts of a sewing machine embodying my 90 invention and it corresponds (so far as the parts are similar) with Fig. 1 of my said Patent No. 1,073,344,

Fig. 2 is an elevation of the primary separating and advancing device,

Fig. 3 is a plan view of the parts shown in Fig. 2,

Fig. 4 is a sectional view taken on the line 4—4 of Fig. 2,

Fig. 5 is an elevation of the bead separating plates forming part of the primary separator,

Fig. 6 is a plan view of the final separating device,

Fig. 7 is a side elevation thereof,

Fig. 8 is an inverted plan view thereof,

Fig. 9 is a sectional view thereof.

Many of the parts of the sewing machine illustrated herein are similar to parts of the machine shown in my said Patent No. 110 1,073,344 and in so far as the parts in the present case correspond with those of said

patent they are similarly numbered. Inasmuch as the present invention may be applied to a machine like that of my said patent by merely adding certain parts and by substituting others in similar relations it is not necessary to here describe in detail all parts of the complete machine but only such parts as may be necessary to the proper understanding of the additional or substituted features.

As is set forth in my said Patent No. 1,041,780 the machine is intended to attach strung articles, such as beads, to a fabric by stitches, and as set forth in my Patent No. 1,073,344 the machine may be employed to attach the articles either in straight lines or in any other formation.

In the present case I have shown an upright rod 98 near the right hand end of the machine and supported from the frame thereof. This rod forms a support for a bracket 99 which is adjustable thereon; and for a second bracket 100 which is also adjustable thereon. The bracket 99 carries the forks 101 provided with an arbor 102 on which the reel 103 with the supply of thread and beads is adapted to revolve. A friction shoe 104 is pressed against the reel 103 to put a slight tension thereon to prevent the reel from turning faster than required to let off the string of beads. The beads 26 are loosely strung on a thread 26^a and the strung beads on the reel 103 are intended to furnish the supply necessary for the operation of the machine.

The bracket 100 forms one of the supports (the upper one) for a trough 105 which guides the beads from the reel 103 to a point over the stitching mechanism.

40 There is a bracket 106 fixed to the machine frame near the left hand end, and at its top there is arranged a stationary arm 107 which forms one of the supports for the trough.

45 The trough 105 is intended to form a guide and support for the beads. It has upright side walls 108 spaced sufficiently to receive the largest beads likely to be used, and it has a V-shaped bottom 109 which will cause the string of beads to center in the trough so that they will approach the primary separating device in regular order, *i. e.*, in a row.

50 The device for primarily separating the beads upon their thread consists of the following:

The bracket 106 has a bearing for a shaft 110 and the latter has an arm 111 fixed thereto and extending outwardly. A link 112 is fulcrumed to the arm 111 at one end and at its other end it is fulcrumed to an arm 60 which is an extension of the lever arm of the lever 60-62 of my said Patent No. 1,073,344. As this lever is operated periodically by the cam 48 on the main shaft 3, the

arm 60 operates the link 112 and thus rocks the shaft 110 in time with the stitching operations of the machine. It is to be understood that the arm 60 in the present case is used to move the shaft 110 in addition to 70 the function which it performs in my said patent.

There are fixed on the shaft 110 two plates 113 and 114 one lying in advance of the other a distance equal to the length of 75 an individual bead. The inner edges 115 of these plates break joint or are arranged in overlapping planes and each plate has an arcuate slot 116 curved concentrically with the shaft 110. These slots extend from the 80 edges 115 of the plates and each is wide enough to allow the bead thread to pass free therethrough but narrow enough to prevent a bead from passing through. Each time the shaft 110 is rocked both backwardly and forwardly (which it will be upon a complete stitching operation of the machine) a single bead will be separated from the oncoming beads and it will be allowed to pass this separating device, the 85 remaining beads being held back. If the plates 113, 114 are in their extreme left position, viewing the parts in plan, then the bead thread will extend from the trough 105 through slot 116 in the plate 114 and the lowermost bead will rest against the plate 114 (the remaining beads resting against this lower one) and the inner edge 115 of the plate 113 will be in line with the rear end of the lowermost bead. If the shaft 110 90 is now rocked to move the plates 113, 114 to the right, the plate 113, will cut in between the lowermost bead (the one just held back by the plate 114) and the bead just behind it. The beads in the trough will now be 95 held back by the plate 113 instead of the plate 114, and when the latter moves toward the right hand position it will have cleared the lowermost bead. The latter being no longer held back, will move down on the 100 thread. Upon the reverse motion of the shaft 110 and plates, 113, 114 (toward the left when viewed as in Fig. 3) then the plate 114 will again straddle the thread and come into the path of the beads; and the plate 113 105 will withdraw from the path of the beads, allowing them to move down against the plate 114. Each time the plates 113, 114 110 make a complete movement to the right and left a bead is allowed to pass in the manner described, but only one can pass as the others are held back. If two or more beads are to be fed at each operation it is only necessary to separate the plates 113, 114 so that the one lies behind the other the length 115 of two or more beads.

The bead thread leads from the upper separator to a novel guiding device which permits the thread to change to a vertical or nearly vertical direction. On the bracket 120

106 there is fixed an arm 117 which extends around the separating device and which has its free end 118 extending at right angle to the bead thread. There is an idler 119 5 mounted on the end 118 and adapted to be turned freely by the bead thread. This idler has transverse grooves 120 which may be spaced to correspond substantially with the length of a bead and it has a peripheral 10 groove 121 in which the thread may lie. As the thread travels around the idler 119 it causes the latter to revolve and the beads enter singly in the transverse grooves 120 and they also leave the idler one at a time 15 where the thread leaves the idler. The beads drop singly down the vertical run of the thread and through the shaft 37 toward the stitching mechanism.

The lower separator which is associated 20 directly with the stitching mechanism may be operated in a similar manner to the separator in my said Patent No. 1,073,344. There is an annular ring 69 which is supported from the bracket 69^a and this ring forms a 25 bearing for the separator plate 73. The latter includes an annular ring portion 66 which has gear teeth 67 on its upper surface and the gear 90 on the shaft 89 is adapted to act on these teeth for the purpose of revolving 30 the separator plate to correspond with the changes in the direction of feed of the fabric and the changes in the direction of stitching. The gear 90 may be connected to and operated by the same actuating devices 35 as those shown in my said later patent to operate the present separator in a similar manner and for the same purpose that the separator is operated in my said later patent.

The separator in addition to the ring 66 40 has an inwardly extending neck 72 which carries the inner plate 73. The latter has a central aperture 73^a into which the sewing needle or hook 10 may pass. The outer edge 122 of the plate 73 is circular for the greater 45 portion of its circumference, preferably concentric with the path of the needle, and it extends inwardly at 123 from the circular portion. The member for cutting off or separating a bead between successive stitches 50 comprises a plate 124 secured to the plate 73 and below the upper circular edge 122 of the latter. The distance of the plate 124 below that of the edge 122 corresponds with the length of a single bead if one bead is to be 55 fed after each stitch, or, if two or more beads are to be fed after each stitch then the plate 124 will be lowered accordingly. This plate 124 lies under the cut away portion 123 of the plate 73 and it is slotted at 125 to provide 60 the supporting portion 125' and an outer supporting portion 126.

The under side of the plate 73 is provided with means for advancing the beads down along their thread and it is arranged to act 65 on the beads between the separator and the

point where the needle enters the fabric. In the form of my invention herein illustrated this comprises a downward extension 127 on the under side of the plate 73 the extension having a guiding edge 128 which acts like a cam on the beads. It commences near the plate 73 at the point 129 and extends downward, with its lowest point at 130 which is near the needle aperture 73^a. The looper 25 is preferably the same as that shown in my 70 said Patent No. 1,073,344 and it may be operated by the same mechanism and for more detailed description thereof reference may be had to said patent.

The sewing needle or hook 10 shown here- 80 in may be operated the same manner as in my said later patent and in so far as the operating parts are shown herein they are lettered the same as in said patent.

I have previously set forth the operation 85 of the primary feeding and separating device and I will here set forth the operation of those parts which finally separate and feed the beads.

The looper body 23 is oscillated by the 90 worm 27 which reciprocates with the shaft 28, so that it makes somewhat less than a complete revolution and the looper oscillations are controlled according to the change in the direction of feeding of the fabric, by 95 revolving the shaft 28 in the manner set forth in my said later patent. It will be understood that the worm 27 operates on a worm 22 on the looper body 23 the same as in said patent.

The bead thread leading from the idler 119 passes down through the hollow shaft 37 and when a stitch has been made in the fabric the thread leads from the hollow shaft 37 and through the looper 25 to the 105 point of the last stitch in the fabric. Assuming the machine has been properly supplied with the thread having the beads loosely strung thereon and that stitches have been made in the fabric, each complete operation of the machine may be traced as follows: The beads, generally at least several in number, which have been fed to the vertical run of the thread drop down so that the lowermost bead rests on the plate 110 73 or the plate 124 and several others rest 115 down on the lowermost bead. If the delivery end of the looper 25 is near the inner end of the slot 125 in the plate 124 the beads will rest on this plate, the thread leading 120 from the end of the looper through the slot 125 and to the point of the last stitch in the fabric. At about this moment or immediately after, the sewing hook 10 is moved upwardly through the fabric and into the 125 aperture 73^a. The looper 25 will then turn clockwise (as viewed from above), so that the thread is moved from the point 131 out of the slot 125 and around the circular edge 122 to about the point 132; and this will 130

loop the thread around the sewing hook 10. The latter will then be withdrawn downwardly through and out of the fabric, forming a switch. On the return oscillation of 5 the looper the thread will be carried around the circular edge 122, counterclockwise, from the point 132 to the point 131 within the slot 125. When the first or clockwise movement of the looper takes place, the 10 lowermost bead is resting on the plate 124 and when the thread commences to rest against the circular edge 122 of the plate 73 this edge cuts in between the lowermost bead and the one next above it and as the 15 lowermost bead slides off the plate 124 it is no longer supported and it is free to travel down the thread to the fabric below. The succeeding beads, however, are supported on the edge 122 of the plate 73 while the looper 20 is completing its oscillation back and forth around this plate. As soon as the lowermost bead referred to has been cut off or separated by the edge 122 it may slide down the thread as above set forth, but if it should 25 not drop immediately of its own weight it will be engaged by the cam edge 128 and as the looper carries the thread around the edge 122 the edge 128, acting somewhat like a cam, will force the separated bead down 30 the thread so that it arrives at its point of attachment to the fabric by the time the looper carries the thread to the point 132. This insures the positive feed of the bead to its point of attachment at the proper time. 35 In the embodiment of my invention shown herein no action to feed the bead downwardly is required other than the action of the looper in casting the loop around the sewing hook and the co-operation of the cam edge 128; so that the device is not complicated by cumbersome mechanism.

When the looper makes its return movement from the point 132 to the point 131 the 40 beads above the separator will first rest on the edge 122 of the plate 73 and then they will drop one bead length and be supported by the plate 124 until the commencement of another operation of the looper. At each 45 complete oscillation of the looper the above described operations will be repeated. After each stitch there will be a bead fed down the thread to the fabric so that each bead will lie between successive stitches, the same as in the product made on the machine of 50 my said patent.

The present device, so far as the final separator is concerned, differs from my said 55 patents, in that I provide the cam member 128 and in so far as the plate 124 engages the thread not only from the inside but also from the outside, *i.e.*, I have added the part 60 60. The advantage of this is, that if there should be a slight slack in the thread while it is held in the slot 125 or if there should 65 be a slight thrust of the beads as the looper

reaches the slot 125 the beads will not be cast off the support 73 and travel down the thread other than as intended.

Except as herein set forth the machine as a whole may be constructed and operated 70 as set forth in my said patents.

While I have described my invention as applied to a machine like that of my prior patent I do not wish to be understood as limiting my invention to such application 75 but I intend to cover all modifications and embodiments which come within the scope of the following claims:

Having described my invention, what I 80 claim is:

1. A bead sewing machine comprising stitching mechanism including a hollow needle shaft through which the string of beads is adapted to be fed, means for holding a supply of strung beads, means over 85 which the string of beads is adapted to engage and by which the string of beads is adapted to be directed toward said needle shaft and a trough for supporting the string of beads, arranged between the supply holding means and said engaging means and inclined downwardly from the end nearest the said supply toward said engaging means.

2. A bead sewing machine comprising 90 stitching mechanism including a hollow needle shaft through which the string of beads is adapted to be fed, means for holding a supply of strung beads, a trough for 95 guiding the string of beads arranged between said supply holding means and said needle shaft and means disposed near the trough and adapted to separate the beads whereby they will be fed periodically toward the stitching mechanism, said trough 100 inclining downwardly from the end nearest the said supply toward said separating means.

3. A bead sewing machine comprising 105 stitching mechanism, means for holding a supply of strung beads, a separator for controlling the feeding of the beads to the stitching mechanism and a trough interposed between said supply holding means and said separator and having inclined portions 110 adapted to align the beads.

4. A bead sewing machine comprising 115 stitching mechanism including a hollow needle shaft through which the string of beads is fed, means for holding a supply of loosely strung beads, and means for controlling the feed of the loosely strung beads to the stitching mechanism, including means for alternately intercepting the beads at different points in their path of 120 movement toward said shaft, means for operating said intercepting means, and a trough for supporting said beads arranged between said supply holding means and said needle shaft, inclined downwardly from 125 130

its end nearest the supply holding means toward said controlling means.

5. A bead sewing machine comprising stitching mechanism and means for engaging a string of beads while feeding to said stitching mechanism, comprising a revolute member against which the string of beads may rest, said revolute member having recesses spaced around the periphery thereof to receive the beads therein, while the latter are passing around the revolute member, said revolute member having a circumferential groove intersecting said recesses and extending inwardly in 10 said revolute member from the tops of said recesses and adapted to receive the bead thread therein.

6. A bead sewing machine comprising stitching mechanism and means for engaging a string of beads while feeding to said stitching mechanism comprising a revolute idler against which the string of beads may rest, said idler having a peripheral groove to receive the bead thread and peripherally spaced recesses to receive the beads, and means for holding a supply of stung beads, arranged whereby the direction of travel of said string of beads will be changed by said idler.

30 7. A bead sewing machine comprising a needle, a thread looper coöperating therewith, means for separating the beads on the sewing thread to control their feeding in relation to the stitching operations, and 35 means for engaging the beads as they are separated and coöperating with said looper to move the beads toward the point of stitching.

8. A bead sewing machine comprising a 40 needle, a thread looper coöperating there-

with, means coöperating with said looper for controlling the feeding of the beads on the sewing thread in relation to the stitching operations, and means coöperating with said looper to move the beads toward the 45 point of stitching.

9. A bead sewing machine comprising a needle, a thread looper for casting loops around said needle, means interposed in the path of the sewing thread as it is moved 50 by said looper and adapted to separate the beads thereon and means between said latter means and the point of stitching and adapted to engage the beads as the sewing thread is moved by said looper and to move 55 them toward the point of stitching.

10. A bead sewing machine comprising a needle, a thread looper for casting loops around said needle, a plate for supporting the beads on the sewing thread, means for 60 separating the beads to control their feed as the looper carries the thread around said needle and a cam member under said plate, adapted to move the beads toward the stitching point as the thread is moved by 65 said looper.

11. A bead sewing machine comprising a needle, a support for holding beads carried by the sewing thread, a looper adapted to cast loops over said needle and to move 70 the thread against said support, and means having a slot and adapted to support the beads on a different level from said first support whereby the latter will separate the beads, said slot being adapted to receive 75 the bead thread as it is moved by said looper.

Signed at the city, county and State of New York this 30th day of October, 1917.

JOSEPH A. GROEBLI.
